Pierre Janssen.

UNITED STATES PATENT OFFICE.

PIERRE JANSSEN, OF NEW YORK, N. Y.

WINDOW-BLIND.

SPECIFICATION forming part of Letters Patent No. 235,151, dated December 7, 1880.

Application filed November 18, 1878.

To all whom it may concern:

Be it known that I, PIERRE JANSSEN, of the city, county, and State of New York, have invented a new and useful Improvement in the Construction of Window-Blinds, which improvement is fully set forth in the following specification, reference being had to the accompanying drawings, in which like letters indicate the same parts.

10 Figure 1 shows a front elevation of my improvement. Fig. 2 represents a section taken on line *w w* of Fig. 1. Fig. 3 shows a section taken on line *x x* of Fig. 1. Fig. 4 represents a section taken on line *y y* of Fig. 5, showing rack and pinion for operating the blind-slats. Fig. 5 shows a transverse section on line *z z* of Fig. 1.

15 The object of my invention is to improve the construction and operation of that class of window-blinds having slats movable on their axes for the purpose of regulating light and ventilation.

In the better class of houses it is common to construct these blinds in such a manner 20 that the mechanism for operating the blind-slats will be entirely concealed, excepting a small knob or thumb-piece, by turning or sliding which the slats in any single section of the blind are all moved to any desired angle 25 or position.

30 My invention relates to an improved construction and combination of the various parts of a blind provided with the above-mentioned slat-operating mechanism; and it consists in a 35 certain combination of parts, as will hereinafter be more fully described, and pointed out in the claim.

A represents the usual outside or main framing of the blind; B, the removable independent rectangular frame to and in which the slats E and their operating mechanism are secured. One end of the slats E have formed on them the usual round tenons, which turn in recesses in one of the side stiles of the frame B. The 45 opposite side stile of this frame is cut or grooved out from the side next the other ends of the slats E, thus forming a pocket or recess, in which the rack and pinions for operating the slats are placed. These pinions D have square 50 orifices, in which a square tenon formed on

the adjacent ends of the slats E is tightly fitted. Circular hubs formed on D loosely fit and turn in corresponding holes made through the plate or strip C, which is secured to the stile of the frame B, as shown. All of the 55 pinions D are caused to turn and move the slats E as may be desired by turning the pinion *f*, which connects with the rack F. By means of the thumb-piece *f'* any other suitable means may be employed for this purpose. 60

I am aware that an independent rectangular framing has been before used to support slats operated by a series of levers, a connecting-rod, and counter-weight, which construction required one stile of the main frame of 65 the blind to be grooved out to admit the slat-operating mechanism within it, said grooving of the main stile greatly reducing its cross-section and materially weakening it, and leaving the whole main frame of the blind more liable 70 to warp, twist, or sag than would be the case in a blind whose side stiles have about the same cross-sectional strength. Another objection to the above arrangement of slat-operating mechanism is, that during the process of 75 manufacturing or adjusting the removable slat-frame to the main frame of the blind, or on the removal of the said slat-frame for readjustment or repairs of the outside main frame, the whole of the slat-operating mechanism is exposed to displacement or injury. It is also 80 very inconvenient to adjust the said mechanism within the grooved main stile. It is therefore desirable, first, not to sacrifice the neat, light appearance of small inside blinds, which 85 have a slat-operating mechanism attached to a removable rectangular frame, in order to introduce said mechanism within the blind; second, it is also desirable that both side stiles of the main frame of the blind be of equal 90 strength, as above set forth; and, third, it is desirable that the slat-operating mechanism be entirely inclosed within one stile of the removable rectangular slat-frame in such manner as shall prevent injury to said mechanism 95 by collision with other objects during the process of manufacture, or when the same is removed from or readjusted to the main frame, as above set forth. These three above-mentioned desirable and important features are 100

secured in the construction of my improved blind, as above set forth and described.

I am also enabled by my arrangement of slat-operating mechanism within the side stile 5 of the inner removable frame to make the complete blind cheaply, and also to make the single side stiles, with the operating mechanism contained therein, separate from any other part of the blind, and ship the said operating 10 stile, at small expense, to distant parts without danger of derangement, where they can be applied by other parties in the manufacture of blinds of this class.

Having thus fully described my invention, 15 what I claim as new, and desire to secure by Letters Patent, is—

The removable frame B, carrying the slats

E, and adapted to be arranged within the main frame A, the tenons of the slats at one end being angular, in combination with the 20 pinions D, through which said angular tenons pass, said pinions having cylindrical hubs fitting and turning within openings in the plate C, which retains all the pinions in position in the removable frame, the continuous vertical 25 rack-bar F engaging the pinions, and the exposed thumb-piece f' , carrying a pinion, f , for operating the rack-bar and imparting motion to the slat-operating pinions, substantially as shown and described.

PIERRE JANSSEN.
